Patented June 26, 1973

227,447

FOLDABLE BOX

Gotz Pinkert, Aschaffenburg, Germany, assignor to Braun Aktiengesellschaft, Frankfurt, Germany

Filed Aug. 27, 1971, Ser. No. 175,805

Claims priority, application Germany Mar. 1, 1971

Term of patent 14 years

Int. Cl. D9—03

U.S. Cl. D9—226

FIG. 1 is a front perspective view of a foldable box showing my new design, with the box partially folded; and

FIG. 2 is a rear perspective view thereof.

The drawing is shaded to indicate contrasting color.

I claim:

The ornamental design for a foldable box, substantially as shown and described.
